UNITED STATES PATENT OFFICE.

LE ROY W. FAIRCHILD, OF NEW YORK, N. Y.

DESIGN FOR A PEN SIGN.

Specification forming part of Design No. 6,539, dated April 1, 1873; application filed October 29, 1872.

To all whom it may concern:

Be it known that I, LE ROY W. FAIRCHILD, of New York, in the county of New York and State of New York, have invented a certain Design for a Pen Sign, of which the following is a specification:

My invention consists in a novel design for a sign; and the design consists in a sign having the name of the dealer painted, printed, or otherwise affixed thereon, with an imitation gold pen suspended therefrom, said pen hav-

ing the name of the manufacturer stamped or lettered thereon, as clearly represented in the accompanying drawing.

What I claim is—

The herein-described design for a sign, as represented in the accompanying drawing.

LE ROY W. FAIRCHILD.
